ATTORNEY.

UNITED STATES PATENT OFFICE

JESSE I. MADDEN, OF ROCKVILLE CENTER, NEW YORK

COMBINED GUIDE AND CLEANER

Application filed September 21, 1928. Serial No. 307,543.

My invention, broadly speaking, relates to textile devices, and more specifically to what may be termed a combined guide and cleaner for winding machines.

5 In the textile art, the first manufacturing process is the "winding" or "throwing" of the thread or yarn, by which it is taken from the skein or hank and wound upon a spool, cone, or package. In this process it is very 10 important that the thread or yarn be cleaned of all snarls, nibs, slugs, dirt or other foreign matter which may be adhering to it, so that the cone or package will be perfect and clean.

15 There are a number of devices in use by the trade for this cleaning process, and these devices are commonly known as "cleaners". They all include in their make-up some kind of metal attachment for effecting the actual cleaning. Often the body of the device is 20 of porcelain with metal attachment, or vice versa.

25 The winding or throwing above referred to, is done on winding machines, and these machines are provided with "winder guides" to keep the thread from coming in contact with any rough part of the machine, and to hold it in perfect alinement, so that a perfect cone or package will be wound. These "winder guides" are of various designs, but they 30 all have a single object, namely; for winding purposes, as their name indicates, and as just above stated.

35 During this winding process the cleaners mentioned above are employed to operate upon the thread. They are suitably held either in front or at the back of the "winder guides", and all of them are provided with some kind of a metal edge. This metal edge is so arranged that a parallel piece of porcelain cooperates with it, but the metal edge is really the part that does the cleaning—the porcelain serving to hold the thread to the metal while the metal operates on it.

45 The great advantage of this piece of metal is that it can be given a fine edge but it has a very objectionable feature which more than counteracts this advantage, for it will not stand up to this kind of service. No matter how hard the metal may be tempered, or how 50 highly it may be polished, it is bound to be

cut by the thread in a very short time; and it is a matter of common knowledge that where metal is cut by the thread in this way, a knife-like edge will be quickly formed, so that in almost no time, this edge will be cutting—chafing—the silk or other thread. This will take place long before any defect in the metal edge can be discovered with the naked eye; so that it is necessary to make frequent examinations of these edges with a magnifying glass. This latter is often overlooked, or put off too long; and hence the outcome of it all is that in the majority of cases the objectionable edge is not discovered until a number of imperfect cones or packages have been 65 wound; for the edge will not at first, or for quite a while after, cut the thread entirely in two, which will not take place till a pronounced edge has been formed; but while the metal is wearing to this sharp edge, it will 70 rake and cut and chafe the surface of the thread till it makes it rough and frizzly.

75 The object of the present invention is to provide a single all-porcelain device which will at once perform all the functions of both a winder-guide and a cleaner, as the functions of these two have been above outlined. So far as I am aware, it is the first and only all-porcelain winder-guide in existence; and when it is used there will be no need of any 80 other attachment or accessory for cleaning purposes, since it performs both functions. Hence, with a one-piece porcelain cleaner-guide, where heretofore at least two and sometimes three attachments had to be assembled 85 to make a cleaner-guide, the cost will, of course, be much cheaper and the labor of attaching much less.

90 As a rule, cleaner guides employing metal must be set with what is termed a "feeler gauge", and it requires a skilled mechanic to read this gauge, and to accurately adjust the metal parts of the guides true to a certain number of thousandths of an inch.

95 My guide bears a number indicating the gauge of the drill hole or cleaner hole, so that in order to have the correct gauge it is only necessary to select a guide bearing the proper number; and properly placing the guide on the machine is so simple that a child can do 100

it—not the slightest need of any skilled mechanic for that.

A leading feature of the invention consists of a porcelain block having a gauged bore 5 with a guide slot leading thereinto.

The invention consists in certain novel features of construction and arrangement, as will be hereinafter described and claimed, reference being had to the accompanying 10 drawings, in which;—

Fig. 1 is a top plan view of my combined guide and cleaner.

Fig. 2 is a perspective on a slightly enlarged scale showing the front side of the device.

Fig. 3 is a perspective, taken at a different angle, and showing the rear side of the device.

Fig. 4 is a front elevation, and;

Fig. 5 is a rear elevation.

20 The device is made preferably entirely of a single piece of porcelain. As more clearly shown in Figs. 2 and 3, it is comparatively wide at the bottom and comparatively narrow at the top.

25 The bottom is provided with a longitudinal V-shaped groove 1 to adapt it for mounting on the frame of the machine with which it is to be used. At its top the device is provided with a small longitudinal groove 2 for the 30 reception of the ends of the holding wires such as are usually employed for holding the winding guides on the frame of a winding machine.

The pull on a winder guide is, of course, always toward the rear, and hence the front side 3 of the guide is made a trifle higher than the rear side 4, in order to present to the holding wire a slightly broader face on the side of the groove 2 which resists that rearward 40 strain.

45 At its longitudinal centre the device is provided with a vertical slot 5 which is flared at its upper end for the easy reception of a thread, but which becomes gradually narrower toward its lower end where it terminates in a transverse bore 6. This bore is accurately formed, and is made of different gauges according to the number of the thread with which each individual gauge is to be used. 50 And in practice, that number is stamped on the guide, so that there may be no mistake or difficulty in getting the proper guide for any given kind of thread.

55 The device is provided on its front side with a recess 7 having its walls tapering inwardly to the slot 5 and the gauged bore 6, while on its rear side it has a still broader recess 8 which has a flat vertical bottom lying 60 on the two sides of the slot 5.

By virtue of the two recesses 7 and 8, formed as just described, the opposing walls of the slot 5 are very narrow coming to what may be termed a rounded edge; and the porcelain on each side of the slot is of chisel forma-

tion—flat on the rear side of a rounded edge, and beveled on the front side.

In operation, the thread is passed down through the slot 5 into the bore 6 which serves the double purpose of cleaning the thread 70 while at the same time forming a winder guide therefor.

Due to the superb wearing qualities of porcelain, the bore 6 will not be soon cut away by the action of the thread upon it; and yet 75 the thread will be beautifully cleaned; and the cones or packages will all contain thread of a smooth and even finish, from which a finer manufactured product is made than would be possible to make from thread chafed and frazzled on its surface by a metallic cleaner.

80 From the foregoing, it will be seen that I have provided a single all-porcelain device which takes the place of two or three devices, as ordinarily used; a device which is simple, cheap and durable; does not require an expert or skilled mechanic to adjust or use it; and withal does very fine work.

Having now described my invention, what I claim as new and desire to protect by Letters Patent is:—

1. A thread cleaner, formed of a single piece of porcelain, and having a transverse gauged bore with a guide-slot leading thereinto.

2. A thread cleaner, formed of a single piece of porcelain, and having at its longitudinal centre a transverse gauged bore with a guide slot leading downwardly thereinto, said slot being flared at its upper end and having convergent opposing sides.

3. A device of the character described, formed of a single piece of porcelain, and having at its centre a transverse gauged bore with a guide slot leading downwardly thereinto, said slot being flared at its upper end and having convergent opposing sides, the device being provided with front and rear recesses surrounding said guide slot and bore.

4. A device of the character described, formed of a single piece of porcelain, and having at its longitudinal centre a transverse gauged bore with a guide slot leading downwardly thereinto, said slot being flared at its upper end and having convergent opposing sides; the device being provided on its front side with a recess having its bottom sloping upwardly to said bore and having side walls converging horizontally to said guide slot and extending downwardly to said bore; and on its rear side having a recess, with a flat vertical inner wall surrounding said slot and bore, whereby to render the walls of the guide slot narrow with horizontally convergent walls at its front side and a flat wall at its rear side.

5. A device of the character described, formed of a single piece of porcelain, and having at its longitudinal centre a transverse gauged bore with a guide-slot leading down- 130

wardly thereinto, said slot being flared at its upper end and having convergent opposing sides; the device being provided on its front side with a recess having its bottom sloping upwardly to said bore and having side walls converging horizontally to said guide slot and extending downwardly to said bore; and on its rear side having a recess, with a flat vertical inner wall surrounding said slot and bore, whereby to render the walls of the guide-slot narrow with horizontally convergent walls at its front side and a flat wall at its rear side; said device being comparatively broad at its base and provided with a longitudinal groove for mounting the device on the machine with which it is to be used; and the upper edge of the device being narrow and provided with a longitudinal groove for the reception of holding devices, the front side wall of said groove being higher than the rear wall thereof, to hold the device against the greater lateral strain imposed upon said front wall when the machine is at work with the thread passing transversely through the device from front to rear.

In testimony whereof I affix my signature.
JESSE F. MADDEN.
